UNITED STATES PATENT OFFICE.

HERBERT H. SWAN, OF GRAND RAPIDS, MICHIGAN, ASSIGNOR TO CORDUROY TIRE COMPANY, OF GRAND RAPIDS, MICHIGAN, A CORPORATION OF DELAWARE.

DESIGN FOR A TIRE.

Application filed May 12, 1924. Serial No. 9,555. Term of patent 14 years.

To all whom it may concern:

Be it known that I, HERBERT H. SWAN, a citizen of the United States, residing at Grand Rapids, in the county of Kent and State of Michigan, have invented a new, original, and ornamental Design for Tires, of which the following is a specification, reference being had to the accompanying drawings, forming a part thereof, in which—

Figure 1 is a side view of a portion of a tire showing my new design;

Figure 2 is a development of the same looking toward the rotative axis of the tire;

Figure 3 is a cross-sectional view of the same taken on line 3—3 of Figures 1 and 2.

I claim:

The ornamental design for a tire substantially as shown.

HERBERT H. SWAN.
